UNITED STATES PATENT OFFICE.

EMMETT R. FRANKLIN, OF BINGHAMTON, NEW YORK.

WIRE BASKET.

No. 920,313.

Specification of Letters Patent.

Patented May 4, 1909.

Application filed November 16, 1908. Serial No. 462,802.

To all whom it may concern:

Be it known that I, EMMETT R. FRANKLIN, a citizen of the United States, residing at Binghamton, in the county of Broome and 5 State of New York, have invented certain new and useful Improvements in Wire Baskets, of which the following is a specification.

My invention relates to improvements in wire baskets and particularly to that class of 10 baskets which are used in markets for carrying and delivery baskets.

It consists in certain peculiarities of construction and novel arrangement of parts thereof, as will be hereinafter set forth and 15 specifically claimed.

The object of my invention is to provide such a basket as, while being constructed of wire, or otherwise, will have within it a removable lining so that no matter how large 20 the mesh in the wire weave may be, it will hold the smallest article, and yet have the full strength and durability of a wire metallic receptacle. I attain these objects by the mechanism illustrated in the accompanying 25 drawing, in which—

Figure 1 is a perspective view of my invention. Fig. 2 is a plan view thereof. Fig. 3 is a longitudinal section taken on the line 3—3 of Fig. 2.

Similar letters refer to similar parts 30 throughout the several views.

"A" represents a basket which may be made of wire of uniform size except the marginal rim wire "a" and the base wire "b" to 35 which the strands composing the body portion of the basket are secured; the rim wire "a" and the base wire "b" necessarily are of larger size to give strength to the structure.

In order to have proper and firm handles 40 for the basket, and that the rim wires may be utilized therefor, I leave an opening in the mesh of the wire at each end of the basket, I make this opening by shortening the cross wires "c" and "c'" and "d" and "d'" and 45 twisting the ends of these shortened strands about the cross wires, "e" and "e'" and "f" and "f"'; and thus is left the open spaces "G" and "G'" forming handle holes.

Within the basket I have certain remov-

able side and bottom linings, and to hold 50 these in place I fasten to the interior of the basket across the sides and bottom cross wires "i" and "i'" and across the ends the cross wires "j" and "j'", I then insert flexible lining strips for the sides, one on each 55 side, "H" and "H'" placing these in position by bending the lining and inserting the ends beneath the cross wires "h" and "h'" respectively. In the bottom, I insert the bottom lining strip "I" in the same manner 60 and in the ends, the end lining strips, "J" and "J'" respectively inserting them in the same manner. In this way I have a firm 65 strong basket having all the strength as well as lightness of a wire basket and at the same time capable of holding the smallest article 70 and of being renovated and renewed by the insertion of fresh new lining at any time.

It is obvious that I may use either a square 75 form of basket or a circular form of basket if so desired and that my invention is applicable to other baskets than those composed of wire.

Having thus fully described my invention, what I claim as new and desire to secure by Letters Patent, is as follows:

1. The combination of a basket having across the inner surfaces of its sides, ends and bottom cross wires stretched and beneath which cross wires are inserted flexible 80 strips resting against the inner surface of the sides, ends and bottom, forming in this position removable linings to the interior of the basket.

2. The combination of a basket having 85 handle openings and having across the inner surfaces of its sides, ends and bottom, cross wires stretched; strips of flexible material inserted between the cross wires and against the inner surfaces of the sides, ends and 90 bottom, the strips having openings formed in them to correspond with the handle openings in the sides of the basket.

3. In a market basket composed of wire, the combination of a basket with a number 95 of wires stretched across the inner surfaces of the sides, ends and bottom for the purpose of receiving and holding strips of material

removably placed therein to form a removable lining to the basket.

4. A basket having an upper and a lower rim which are connected by wire strands to form the body of the basket, wires stretching across the inner surface of the sides, ends, and bottom of the basket, said wires being secured to the rims, and flexible strips held

to the sides, ends and bottom by said last named wires.

In testimony whereof I have affixed my signature, in presence of two witnesses.

EMMETT R. FRANKLIN.
